CLAIM

The ornamental design for a display screen or portion thereof with graphical user interface, as shown and described.

DESCRIPTION

FIG. 1 is front view of a display screen or portion thereof with graphical user interface, showing my new design; and, FIG. 2 is a front-enlarged view of a portion of the display screen or portion thereof with graphical user interface thereof.

The outermost broken lines illustrate a display screen or portion thereof and form no part of the claimed design. The

(Continued)

remaining broken lines illustrate portions of the graphical user interface that form no part of the claimed design.

1 Claim, 1 Drawing Sheet
